UNITED STATES PATENT OFFICE.

REUBEN N. ANDERSON, OF YOUNGSTOWN, OHIO.

DESIGN FOR AN AMUSEMENT AEROPLANE.

58,056.

Specification for Design.

Patented June 7, 1921.

Application filed February 21, 1921. Serial No. 446,962. Term of patent 7 years.

To all whom it may concern:

Be it known that I, REUBEN N. ANDERSON, a citizen of the United States, residing at Youngstown, in the county of Mahoning and State of Ohio, have invented a new, original, and ornamental Design for an Amusement Aeroplane, of which the following is a specification, reference being had to the accompanying drawing, forming part thereof.

The figure is a perspective view of an amusement aeroplane, showing my new design.

I claim:

The design for an amusement aeroplane, as shown.

REUBEN N. ANDERSON.
